UNITED STATES PATENT OFFICE.

BENJAMIN H. BECKER AND JOHN CIESLA, OF CHICAGO, ILLINOIS, ASSIGNEES TO
JAMES S. KIRK & CO., OF CHICAGO, ILLINOIS, A CORPORATION OF ILLINOIS.

SOAP-PRESS.

1,085,236.

Specification of Letters Patent.

Patented Jan. 27, 1914.

Application filed February 3, 1912. Serial No. 675,142.

To all whom it may concern:

Be it known that we, BENJAMIN H. BECKER and JOHN CIESLA, both citizens of the United States, residing in Chicago, county of Cook, and State of Illinois, have invented certain new and useful Improvements in Soap-Presses, of which the following is a specification.

Our invention relates to improvements in that class of presses which are used in the final steps of the manufacture of soap in cake form to give the cake of soap its final or finished form and impress thereon characters indicating its source of manufacture, brand, etc.; and the main object of the invention is to provide, in a machine of this character, an improved and readily adjustable mechanism for effecting the accurate positioning of blanks of different widths between the upper and lower die-members preliminary to the pressing operation, and for controlling the movement or operation of said blank-positioning means so as to effect the release of the blank at the proper point in the movement of the upper reciprocating die-member.

Minor objects of the invention are to provide an improved feed-chute for the blanks, capable of convenient adjustment to blanks of different sizes, to provide simplified and improved means for actuating the reciprocating pusher by which the blanks are successively fed between the dies and the finished cakes simultaneously ejected from between the dies; to provide an improved mechanism for delivering the finished cakes from between the dies; and, generally, to provide an improved, simplified, and highly efficient machine of the character specified.

Our invention, its mode of operation, and the advantages secured thereby will all be readily understood when considered in connection with the accompanying drawings which illustrate one improved form in which the invention may be embodied, and in which—

Figure 1 is a front elevational view of the complete machine. Fig. 2 is a side elevational view, viewed from the right of Fig. 1. Fig. 3 is an enlarged horizontal section on the line 3—3 of Fig. 1. Fig. 4 is an enlarged detail, partly in elevation and partly in vertical section of the upper and lower die-

members and the supports and actuating mechanism of the lower die-member. Fig. 5 is a detail rear elevation of the feed-chute and its adjustable supports.

Referring to the drawings, 5 designates each of a pair of skeleton side frame members rigidly connected at their upper ends by a table or platform 6, on which latter is secured a die-box or matrix 7. Rigidly bolted to the table 6 are a pair of parallel upright frame members 8, best shown in Fig. 2, the forwardly projecting ends of which support a vertical slide-way 9, in which is reciprocably mounted a cross-head 10, to the lower end of which is secured the upper die-member 11. Said cross-head 10 has formed therein a vertical slot 12 that is engaged by the actuating means next to be described. Pivotedly mounted between the standards 8 on a pivot-shaft 13 is a rocking-beam here taking the form of a three-arm lever, the forwardly extending arm 14 of which projects at its free end through the slot 12 of the cross-head 10 and constitutes the immediate actuating means of said cross-head. An upwardly and rearwardly extending arm 15 of said lever carries a counter-weight 16 designed to balance the cross-head 10 and the parts carried thereby; and a long depending arm 17 of said lever is connected to the lever-actuating means herein shown as comprising an eccentric 18 fast on a driving-shaft 19 journaled in suitable bearings 20 on rearward extensions 5^a of the side frames 5, an eccentric strap 21, and a connecting rod 22, between the eccentric strap and the lower end of the lever arm 17 in which connecting rod is interposed the usual elastic slip-joint 23 commonly employed in these machines to reduce jar and vibration and prevent pounding.

24 designates the lower die-member (Fig. 4), secured on the upper end of a stem 25 that is slidably mounted in a bushing 26 threaded through the table 6 and at its upper end forming a stop for the lower side of the die-member 24. The lower end of the bushing 26 has a head 27 by which it may be turned to adjust the position of the die-member 24 upwardly or downwardly, a lock-nut 28 on said bushing serving to lock the same in adjusted position. Fast on the stem 25 is a tappet 29 having a squared

lower end and a tapered or beveled upper end 29^a. The lower end of the stem 25 of the lower die-member is guidingly supported in a depending bracket 30 secured to the lower side of the table 6.

5 The lower die-member 24 is raised to carry the compressed cake out of the matrix 7 and to a position to be ejected from between the die-members by mechanism connected to and actuated from the cross-head 10 and engaging the tappet 29. This mechanism comprises an arm 31 (Fig. 1) rigidly bolted to the upper end of the cross-head 10, a vertical rod 32 connected to the arm 31 10 by a collar 31^a on said arm and a set-screw 33, said rod 32 being guided in a vertical bearing 34 secured to one of the frame uprights 8, and an arm 35 pivoted on the rod 32 near the lower end of the latter. The free 15 end of arm 35 is normally urged toward the die stem by a spring 36 connected to a rearward extension 37 of the arm 35 and to a bracket 38 secured to the lower end of the rod 32. Hence, it will be seen that the 20 lifter-rod 32 is positively actuated in both directions by and from the cross-head 10. As the cross-head approaches the limit of its downward movement, the free end of arm 35 slides over the beveled top 29^a of the 25 tappet 29 and engages the latter from beneath, and as the cross-head rises, the arm 35 rises, raising the tappet, the stem 25, and the lower die-member 24 for the elevation of the pressed blank out of the die-box. As 30 soon as this has been accomplished, the arm 35 is disengaged from beneath the tappet 29, by a kicker 39 that consists simply of a long rigid finger attached to the depending arm 17 of the rocking-beam near its lower 35 end, the free forward end of said kicker striking the inner side of the arm 35 at the proper instant and dislodging it from engagement with the underside of the tappet 29. This allows the lower die-box, its stem, 40 and the tappet 29 to drop by gravity. To cushion the fall of the lower die-member and its stem, the latter is provided with a collar 40 fast thereon which engages the upper end of a cushioning-spring 41 that rests upon 45 the hanger-bracket 30 and is supported by a guide-rod 42 on the bracket 30 and extending through an aperture in the collar 40. This spring 41 does not arrest or impede the full downward movement of the lower 50 die-member and its stem but merely cushions the shock of the fall and prevents pounding either of the tappet 29 on the bracket 30 or of the die-member 24 on the upper end of the bushing 26.

60 Secured to the upper face of the table 6 is an angle-piece 43 (Fig. 3), to the vertical wall of which is secured by bolts 44, angle-bracket 45 and bolts 46, a horizontal shelf 47 that constitutes a rest for the lower end 65 of a feed chute, the parallel side walls of

which are designated by 48, the lower ends of said side walls 48 being secured to the plate 47 with capacity for adjustment toward and from each other by angle-brackets 49, bolts 50 securing said angle-brackets to the shelf 47, and bolts 51 connecting said angle-brackets to the side walls 48. The bottom of the chute is constituted by a pair of rails 52 adjustably secured to the walls by screws 53 entered into said strips and engaged with horizontal slots 54 formed in the side walls 48. By shifting the screws along the slots the depth of the chute can be adjusted according to the length of the blanks to be operated upon.

80 The rear and upper end of the chute is supported from an auxiliary platform 55 secured to one of the frame members 5 by means of a pair of angle-strips 56 secured at their upper ends to the side walls 48 and 85 at their lower ends having short laterally projecting arms 57 apertured to engage a cross-rod 58 (Fig. 5), said cross-rod being mounted in a pair of collars 59 slidably mounted on vertical rods 60 secured to the auxiliary platform 55. The arms 57 are adjustably secured on the rod 58 by set-screws 61, and the collars 59 are adjustably secured on the rod 60 by set-screws 62. This mechanism permits ready adjustment of the 95 width of the chute so far as concerns the supporting means of the upper end of the latter.

90 The shelf 47 extends beneath the bottom end of the feed-chute and forms a support on which the lowermost blank rests; and over said shelf reciprocates a pusher or plunger in the form of a flat strip 64 having a downwardly turned forward end 64^a adapted to engage the rear end of the lowermost blank and push it over the matrix between the die-members. The pusher 64 is secured by means of a collar 65 at its rear end and a set-screw 66 to a rod 67 reciprocably mounted in bearings 68 and 69 carried by 100 the auxiliary platform 55. The plunger is actuated by the following mechanism. Keyed on the driving shaft 19 is a bevel gear 70 which drives a bevel gear 71 fast on a counter-shaft 72, the inner end of which 105 latter has a crank-arm 73 connected by a pitman 74 and collar 75 to an upright rod 76 that is pivoted at its lower end at 77 to a bracket 78 on one of the frame members 5. The upper end of the rod 76 is adjustably 110 connected to the reciprocating rod 67 of the pusher by a collar 79 secured on the upper end of rod 76 by a set-screw 80, a collar 81 secured on rod 67 by a set-screw 82, and a link 83 pivotally connecting said collars.

115 Referring now to the blank centering and controlling means, 84 designates each of a pair of arms having vertical hubs 85 by which they are mounted on pivot-studs 86 carried by blocks 87 that are adjustably 120

secured on a cross-shaft 88 by means of set-screws 89. The inner sides of the arms 84 are provided with non-metallic facing blocks or pads, preferably of rubber, and indicated at 90. The arms 84 have outwardly turned extensions 84^a, to the ends of which are secured depending cams 91. The centering arms 84 are normally urged inwardly or toward each other across the upper side of the matrix by means of compression springs 92 encircling rods 93, said rods being carried at their outer ends in uprights 94 secured to the table 6 and at their inner ends slidably engaging with a loose fit bearings 95 carried by the extensions 84^a of the arms 84, said springs 92 abutting at one end against the bearings 95 and at their other ends against collars 96 secured on the rods 93. We also preferably employ auxiliary spring means for actuating the centering arms in their closing movement comprising tension springs 97 secured at one end to rearwardly extending arms 98 on the hubs 85, and anchored at their other ends to adjustable screws 99 mounted in fixed brackets 100 secured to the table 6. The inward swing of the centering arms is adjusted and limited, according to the width of the blank operated upon, by adjustable stops in the form of screws 101 passing through depending lugs 84^b on the arms 84.

The means for spreading the centering arms comprises a rock-shaft 102 journaled in upright brackets 103 secured to the table 6 and having keyed thereon a pair of arms 104 that coöperate with the cams 91, the upward swing of said arms engaging the inclined surfaces of the cams and spreading the centering arms 84 in opposition to the springs 92 and 97, and the downward swing of said arms permitting the centering arms 84 to approach each other under the impulse of said springs. The rock-shaft 102 is oscillated from the vertically reciprocating rod 32 by means of a vertical link 105 attached near the lower end of the rod 32 as through a collar 106, the upper end of said link being pivotally connected to an arm 107 fast on one end of the rock-shaft 102. From this it will be apparent that the downward movement of the rod 32 will actuate the rock-shaft 102 in a direction to spread the centering arms, while the opposite movement of the rod 32 will permit the inward or closing movement of the centering arms.

The machine is provided with a discharge conveyer for the pressed cakes, the same comprising an endless belt 108 mounted on rollers 109 and 110, the upper section of said belt operating between stationary side guides 111 carried by a bracket 112 secured to the main table or platform 6. The belt is driven by driving connections from the main shaft 19 comprising a bevel gear 113

on shaft 19 meshing with a bevel gear 114 on a counter-shaft 115 suitably journaled in bearings carried by the side frame 5 and 5^a, a sprocket 116 on the shaft 115, a sprocket 117 on the shaft of the roller 110, and a connecting sprocket chain 118.

In the operation of the machine blanks are supplied to the upper portion of the feed-chute, as indicated in Fig. 1, and, as the upper die-member rises, the pusher forces the lowermost blank to a position directly over the matrix and between the upper and lower die-members, the blank being lightly supported at its edges by the pads 90 of the centering arms 84, which are so adjusted as to accurately position the blank exactly over the cavity of the matrix. As the upper plunger descends, the centering arms are gradually spread allowing the blank to drop into the matrix and on to the lower die-member closely followed by the upper plunger, whereupon the compressing and cake-forming operation takes place. As soon as this is completed, the upper and lower die-members simultaneously rise, the lower die-member being elevated by the arm 85 engaging beneath the tappet 29. By this means the finished cake is elevated to a position between the spreader-shoes 90, the lower die instantly dropping back as soon as the arm 35 has been disengaged from the tappet 29 by the kicker 39. The finished cake is lightly gripped between the shoes of the centering arms until the next inward movement of the pusher, forcing a new blank into position, at the same time forces the finished cake out from between the centering arms onto the conveyer 108, whence it is carried off.

A leading advantage of the machine resides in the ready adjustability of the feed chute and centering devices and the actuating mechanism of the latter to accommodate blanks of considerably varying sizes, thus increasing the capability of the machine to handle blanks of varying dimensions. It will be noted that the actuating mechanism of the reciprocating pusher is almost wholly located below the horizontal table or platform of the machine and very low in the latter. This contributes in a large measure to the stability of the machine and its freedom from jar and vibration. It will also be observed that the described actuating mechanism of the machine is readily capable of adjustment to vary the length of stroke of the pusher (according to the length of the blanks used) by simply adjusting the point of connection of the collar 75 lengthwise of the vibrating rod 76. The action of the machine is entirely automatic, the various coöoperating parts being adjusted to operate in properly timed relation; and the machine requires only an attendant to feed blanks into the upper end of the 130

feed-chute, and another attendant to withdraw the finished cakes from the delivery conveyer for wrapping and packaging.

It will be manifest to those skilled in the art that the machine of our invention may be modified in respect to details without departing from the operative principles involved or subtracting from the benefits and advantages attained. Hence, we do not limit the invention to the exact mechanism shown and described, except to the extent clearly indicated in specific claims.

We claim—

1. In a soap-press, the combination with a matrix and upper and lower die-members, of a reciprocating cross-head carrying said upper die-member, means for actuating said cross-head, means for raising the lower die-member after the stamping operation to 15 expel the stamped cake from the matrix, a feed-chute for the blanks, a pusher operating across said feed-chute, a pair of pivoted blank-centering arms disposed on either side of the upper end of said matrix, respectively, means for adjusting said centering arms bodily toward and from each other according to the width of the blanks used, 20 spring means normally urging said arms toward each other, and cam means coöperating with the outer ends of said arms for 25 spreading the latter during the descent of the upper die-member.

2. In a soap-press, the combination with a matrix and upper and lower die-members, 30 of a reciprocating cross-head carrying said upper die-member, means for actuating said cross-head, means for raising the lower die-member after the stamping operation to 35 expel the stamped cake from the matrix, a feed-chute for the blanks, a pusher operating across said feed-chute, a pair of pivoted blank-centering arms disposed on either side of the upper end of said matrix, respectively, 40 spring means normally urging said arms toward each other, a rock-shaft journaled opposite and transversely of the outer ends of said arms, coöperating devices 45 on the outer ends of said arms and on said rock-shaft for effecting the spreading of 50 said arms by cam action, and means for actuating said rock-shaft in suitably timed

relation to the movements of the die-members.

3. In a soap-press, the combination with a matrix and upper and lower die-members, 55 of a reciprocating cross-head carrying said upper die-member, means for actuating said cross-head, means for raising the lower die-member after the stamping operation to 60 expel the stamped cake from the matrix, a feed-chute for the blanks, a pusher operating across said feed-chute, a pair of pivoted blank-centering arms disposed on either side of the upper end of said matrix, respectively, 65 spring means normally swinging said arms toward each other, a rock-snaft journaled opposite and transversely of the outer ends of said arms, cams on the outer ends of said arms, cam-actuating arms on said rock-shaft, and means connected to and 70 actuated by said cross-head for actuating said rock-shaft in suitably timed relation to the movements of the die-members.

4. In a soap-press, the combination with a matrix and upper and lower die-members, 75 of a reciprocating cross-head carrying said upper die-member, means for actuating said cross-head, means for raising the lower die-member after the stamping operation to 80 expel the stamped cake from the matrix, a feed-chute for the blanks, a pusher operating across said feed-chute, a pair of pivoted blank-centering arms disposed on either side of the upper end of said matrix, respectively, 85 means for adjusting said centering arms bodily toward and from each other, spring means normally urging said arms toward each other, a rock-shaft journaled opposite and transversely of the outer ends of said arms, cams on the outer ends 90 of said arms, cam-actuating arms mounted on and adjustable lengthwise of said rock-shaft, and means connected to and actuated by said cross-head for actuating said rock-shaft in suitably timed relation to the movements of the die-members. 95
